UNITED STATES PATENT OFFICE.

WYNNE HOLCOMB, OF NEW YORK, N. Y.

DESIGN FOR A PURSE.

Application filed December 30, 1927. Serial No. 24,702. Term of patent 3½ years.

To all whom it may concern:

Be it known that I, WYNNE HOLCOMB, a citizen of the United States, residing at New York, in the county of New York and State of New York, have invented a new, original, and ornamental Design for a Purse, of which the following is a specification, reference being had to the accompanying drawing, forming part thereof.

I claim:

The ornamental design for a purse, as shown.

WYNNE HOLCOMB.
